UNITED STATES PATENT OFFICE.

RICHARD GARRETT COTTER, OF SAUSALITO, CALIFORNIA.

LADDER.

1,217,713.

Specification of Letters Patent. Patented Feb. 27, 1917.

Application filed July 19, 1915. Serial No. 40,752.

To all whom it may concern:

Be it known that I, RICHARD GARRETT COTTER, a citizen of the United States, residing at Sausalito, in the county of Marin and 5 State of California, have invented a new and useful Improvement in Ladders, of which the following is a full, clear, and exact description.

My invention relates to improvements in 10 ladders used in picking fruits and in the work of pruning trees, and commonly known as fruit or orchard ladders; and the objects of my improvement are, first, to provide a ladder, of any convenient length, of such 15 form that it may be easily and quickly set in any position around or in the head of a tree, enabling the worker to conveniently reach any part of the tree; second, to provide a safe, firm and convenient detachable sup- 20 porting pole, prop or tongue for the ladder; and third, to provide a means of readily and safely attaching or detaching such pole or prop, so that the ladder may be readily and easily set in any position, either around the 25 tree or with its top in among the branches, and the pole placed in proper position among the branches, from the opposite side of the tree and quickly attached, forming a safe and sufficient support for the ladder, 30 or readily detached that the ladder may be set in any new position.

I attain these objects in the manner shown and illustrated in the accompanying drawings, in which—

35 Figure 1 is a view showing the ladder with the pole or prop attached, furnishing a swinging tongue for the ladder as it is swung from position to position around a tree;

40 Fig. 2, an enlarged view of the upper part of ladder, above top step, showing end of pole in position, and the means of attaching and detaching the pole;

45 Fig. 3, a top view of the metal ring or loop "B" into which is screwed the metal coil or screw "C," on the upper end of the pole "D," when attaching the pole to the ladder; and

50 Fig. 4 is a side view of ring or loop "B." In Fig. 2, "C" is a slightly tapering metal coil or screw secured to the upper end

of the pole "D," by means of bolts or rivets; "B" is the ring or loop to engage the coil or screw "C," when the pole is attached to the ladder. The loop "B" is permanently 55 attached to the ladder by passing the shanks "A" loosely through holes in the side rails "E," allowing the pole to swing freely when attached to the ladder.

The screw "C" tapers slightly so as to 60 allow the point to readily enter the ring "B" and take up quickly with one or two twists of the pole.

In carrying out this invention in a practical form, it is obvious that the supporting 65 tongue or pole "D" may be securely attached to the ladder by inserting the screw "C" in the ring or loop "B." A twist or two of the pole attaches it firmly, forming a swinging tongue for the ladder as it is 70 placed in various positions about the outer edge of the tree. Also the tapering upper end of the ladder, with the pole detached, may be easily raised among the limbs or branches into any part of the head of the 75 tree, after which the pole is attached in proper position furnishing a safe and proper support for the ladder and obviating all necessity for supporting the ladder against any part of the tree. 80

I do not claim broadly the tapering form of ladder; but I claim:

1. The combination of a tapering form of ladder with a detachable pole or prop, carrying at one end a tapering screw, 85 the small end of ladder carrying a ring or loop to engage the screw, the ring and screw providing a means of readily and securely attaching the pole to the ladder when desired, or detaching it therefrom, all sub- 90 substantially as set forth.

2. A ladder comprising side bars and rungs, and a closed tapering end in combination with a detachable pole or prop, the ladder being provided with a socket near 95 its tapering end adapted to receive the end of and limit further longitudinal motion of the prop.

RICHARD GARRETT COTTER.
